(57) **CLAIM**

The ornamental design for a portion of a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings showing thread portion of the container, the bottom surface of the container, inside the bottom surface of the container and the lower portion of the container illustrate portions of the design that forms no part of the claim.
